UNITED STATES PATENT OFFICE.

FREDERICK POPE, OF NEW YORK, N. Y., AND GEORGE M. POPE, OF MOUNT PLEASANT, GEORGIA; SAID GEORGE M. POPE ASSIGNOR TO ELIA M. POPE, OF BOSTON, MASSACHUSETTS; SAID FREDERICK POPE ASSIGNOR TO SOUTHERN MANUFACTURING COMPANY, OF PITTSBURGH, PENNSYLVANIA, A CORPORATION OF PENNSYLVANIA.

METHOD OF DISTILLING WOOD.

1,085,875.

Specification of Letters Patent.

Patented Feb. 3, 1912.

Application filed June 1, 1910. Serial No. 564,345.

To all whom it may concern:

Be it known that we, FREDERICK POPE, a resident of New York, in the county of New York and State of New York, and GEORGE M. POPE, a resident of Mount Pleasant, in the county of Wayne and State of Georgia, have invented a new and useful Improvement in Methods of Distilling Wood, of which the following is a specification.

10 This invention is a new and useful method for extracting products from wood; such as turpentine, oil, pitch, etc., from pine wood.

The general object of the invention is to provide a method in which a heated bath is circulated over the wood and by means of which the products are extracted from the wood in greater quantities, in less time, with less cost, and with less injury to the fiber 20 of the wood than has heretofore been possible. According to this method the separation of the products from the bath is effected by means of a bath which is non-volatile and perfectly stable at a temperature much higher than that to which it is subjected in the operation, and even under a partial vacuum, and which has a very high specific heat. As a consequence the solution of the desired products in the bath 30 is reduced to the smallest amount and those in solution remain so for the least possible length of time. The bath while in contact with the wood is a homogeneous liquid. It is also possible by this method to extract all the desired products in less time and at much lower temperature than by any other method.

The method will be described in connection with the accompanying drawings 40 which show one form of apparatus suitable for carrying out the process and in which—

Figure 1 is a diagrammatic view of the apparatus, the retort being in transverse section, and Fig. 2 is a longitudinal view 45 through the retort.

The wood to be treated is placed in cars 1 and run into a retort 2 which is preferably long relatively to its width. The ends of the retort are then closed tightly by 50 doors 3 and the hot bath is pumped into the retort through one or more openings 4 in the bottom. The bath, rising, covers the

wood, heating the same and distilling therefrom the desired products. The bath continues to rise until it reaches one or more openings 5 some distance above the top of the wood, and passes out through these openings to a storage tank 6 from which it is drawn by a pump 7 and forced through a heater 8 where it is re-heated to the desired temperature, and then back into the retort through the openings in the bottom. The retort is provided with perforated steam pipes 9 at an elevation just above the level of the top of the wood. The perforations in these pipes are preferably located so as to direct the current of escaping steam in an upward direction. The retort is also provided with one or more openings 10 for condenser connections 11 and condensers 12, the openings 10 being some distance above the openings 5 for the escape of the bath, and preferably in the top of the retort. The pipe 13 leading from the heater to the inlet to the retort is provided with a cut-off valve 14. A by-pass pipe 15 provided with valve 16 is arranged to deliver the bath directly from the heater to the storage tank 6, and a drainage pipe 17 provided with a valve 18 connects the bottom of the retort with the storage tank or reservoir. Baffle plates 19 are arranged in proximity to the condenser outlets 10 to prevent the spray and fine particles of bath from escaping into the condenser. An air pump or exhaust 20 is preferably connected to the end of the condensing worm and serves to maintain a pressure less than atmospheric pressure on the bath in the retort.

Any other form of apparatus for treating wood in a retort with a hot bath in circulation will serve to carry out the method.

The bath used in this process is one composed of the pitch which is drawn from the bottom of the retort in the destructive distillation of wood. It is a hard pitch, does not volatilize at a temperature of 700 degrees F., has a very high specific heat, and can be easily handled. Another bath that can be used to advantage is one composed of the hard residuum left when rosin has been destructively distilled and certain of the rosin oils distilled off. This also is a

hard pitch having a high point of volatilization and a high specific heat.

In carrying out the process the bath is circulated upwardly through the retort until all the desired products are obtained. The valves 14, 16 and 18 are then changed to drain the retort and permit the withdrawal of the charge of heated wood and the placing of a fresh charge in the retort, the bath meanwhile being circulated from the heater through the by-pass pipe 15 to the storage tank to maintain its temperature.

In carrying out the process the products which are extracted or heat distilled from the wood by the hot bath escape into the body of the bath and most of them in the form of vapor bubble up through the bath and escape through the opening 10 in the top of the retort and pass thence to the condenser. The partial vacuum maintained in the upper part of the retort facilitates the escape of the vapors and reduces the amount that goes into solution in the bath. Those products which do not escape directly as vapors but are dissolved in the bath are almost immediately distilled therefrom as soon as the bath comes in contact with the steam escaping from the perforated pipes 9. The separation of the dissolved products from the bath is made more sure by placing the outlet of the bath some distance above the level of the steam pipes, thereby insuring a very considerable depth of bath through which the steam must pass and giving time for the equalization of the vapor tensions of the steam and dissolved products. These products which become dissolved in the bath must remain dissolved therein the shortest possible length of time, since they are almost immediately distilled from the bath by means of the steam.

What we claim is:

1. The method of distilling wood consisting in placing the wood in a closed vessel,

circulating through the vessel and over the wood from the bottom upwardly a bath composed of hard pitch, thereby distilling the desired products from the wood, and introducing steam into the portion of the bath above the level of the wood and thereby distilling off therefrom such of the products as have become dissolved therein.

2. The method of distilling wood consisting in placing the wood in a closed vessel, circulating through the vessel and over the wood from the bottom upwardly a bath composed of hard pitch, thereby distilling the desired products from the wood, introducing steam into the portion of the bath above the level of the wood and thereby distilling off therefrom such products as have become dissolved therein, and maintaining above the bath in the vessel a pressure less than atmospheric pressure.

3. The method of distilling wood consisting in placing the wood in a closed vessel, circulating through the vessel and over the wood from the bottom upwardly a hot bath composed of the pitch which flows in liquid form from the bottom of the retort in the destructive distillation of wood, thereby distilling the desired products from the wood, and introducing steam into that portion of the bath above the level of the wood, and thereby distilling off therefrom such of the products as have become dissolved therein.

In testimony whereof, we have hereunto set our hands.
